A. L. BAILEY

IRON

Filed April 22, 1926

*Inventor
Arthur L. Bailey
By *Dee's Spec. Jr.*
attorney*

UNITED STATES PATENT OFFICE.

ARTHUR L. BAILEY, OF JAMAICA PLAIN, MASSACHUSETTS.

IRON.

Application filed April 22, 1926. Serial No. 103,712.

This invention relates to irons of the type which are provided with a back rest or heel stand upon which the iron may be tilted back when not in use. Although particularly adapted for electric irons, the principles of my invention apply to other irons. For the purposes of this application, however, I shall discuss my invention in its relation to the familiar electric iron, although this treatment is merely illustrative and in no way limiting.

With the ordinary electric iron equipped with an attached heel stand, the responsibility of remembering to tilt the iron back onto the stand when not in use is placed upon the user, and if the user neglects to do this, the iron will scorch or burn the material being ironed.

In order to entirely eliminate the human factor by definitely relieving the user of the necessity for deliberately and consciously tilting the iron to a safe position when not in use, I have devised my present invention. According to it, the iron is so counterbalanced as to automatically assume a tilted position back on its heel stand the moment that the user's hand is removed from the handle. This avoids the danger of the user forgetting to tilt the iron to a safe position when not in use, and in this respect the iron recommends itself to the fire underwriters.

In its broadest aspect, therefore, my invention resides in the concept of an iron so constructed and arranged as automatically to assume a safe position when not in use. This concept may be carried out in a variety of counterbalancing arrangements, the simplest being merely to so distribute the weight of the iron, handle and heel stand with reference to the operating plane of the iron that the normal tendency of the iron is to assume its safe position whenever the pressure of the user's hand on the handle is removed. Many variants are possible, however, and in another form of my invention which I shall show and describe, the iron handle itself is constructed in two sections, one of which is rigid with the iron and the other of which is provided with a moving counterweight, and is pivoted at one end and spring-pressed so as automatically to tilt rearwardly and thus tilt the iron back onto the heel stand whenever the user's hand is removed from the handle.

The construction and operation of my

iron, together with selected embodiments thereof which illustrate the principles involved, are described and shown in the accompanying specification and drawings, and the characteristic features of novelty are particularly pointed out in the appended claims. In the drawings:

Fig. 1 is an elevation, partly in section, of an iron of conventional type equipped with one form of my invention, and showing in dotted lines the intermediate position which the counterweighted section of the handle automatically assumes when the user's hand is removed therefrom and in dot and dash lines the final position of the handle section and of the iron itself when the iron has tilted to its safe position.

Fig. 2 is an end view of Fig. 1.

Fig. 3 is a section on the line 3—3 of Fig. 1.

Fig. 4 is a view similar to Fig. 1 of a modification and showing in full and dotted lines the operating and safe positions of the iron, and

Fig. 5 shows a further modification.

I have indicated at 1 the body of an iron of standard type and at 2 the heel stand or back rest which is carried by the iron. This back rest may be constructed in a variety of forms and as shown in Fig. 1 includes a part 3 rising from the heel of the iron, preferably at an angle thereto, and carrying at its upper end a cross-piece 4 which constitutes a fulcrum for the upper section 5 of the two-part handle, the lower section 5^a of which is rigidly attached at 5^b to the iron. In this form of my invention, the upper section 5 is adapted to automatically swing rearwardly on its pivot whenever the pressure of the hand thereon is released, whereby to automatically tilt the iron into a safe position, as shown in dotted lines Fig. 2.

For this purpose, the handle section 5 may be made hollow and may contain a rolling counterweight, here shown as a plurality of lead shot 6, and the pivot for the handle is spring-pressed as indicated at 7. Normally, the pivoted handle section 5 is held down against the fixed handle section 5^a by the pressure of the user's hand in grasping the handle to manipulate the iron, as shown in full lines Fig. 1. When the hand is removed from the handle, the spring 7 swings the handle section 5 rearwardly on its pivot 4 into the dotted line position of

Fig. 1. In this action, the counterweight 6 rolls towards the rear end of the hollow handle section 5 and this change of balance is sufficient to tilt the iron rearwardly onto its back rest as shown in dot and dash lines in Fig. 1.

Inasmuch as the lifting action of the spring 7 is slightly greater than the gravity effect of the counterweight, the handle section 5 normally tends to swing upwardly unless positively held down by the pressure of the user's hand thereon in ironing and thus the tendency of the iron is always towards its safe position.

15 In the embodiment of my invention shown in Fig. 4, the spring-pressed handle section 5 is pivoted to a counterweight 8 extending from the heel stand.

In the modification shown in Fig. 5, the handle 9 is a one-piece handle rigidly attached to the iron, and the counterweight 10 which extends from the heel stand 2 is relied upon solely to accomplish the rearward tilting of the iron to its safe position 25 upon release of the handle.

In all forms, the tendency of the iron is to rock back automatically onto its heel stand when the user's hand is removed from the handle. Thus my iron has a constant 30 tendency towards a safe position and automatically moves to such position upon release of the handle.

These, and various other modifications may obviously be resorted to within the 35 spirit and scope of my invention, as defined by the appended claims.

What I therefore claim and desire to secure by Letters Patent is:

1. In combination, an iron comprising a 40 body having a handle and having a heel stand at the rear of the body of the iron, the rear side of said stand extending upwardly and rearwardly from a point adja-

cent the body of the iron, and a counterweight mounted on the iron above and beyond the heel stand and cooperating with said heel stand to cause the iron bodily to tilt rearwardly and upwardly on to said heel stand upon removal of the operator's hand from the handle.

2. In combination, an iron comprising a body having a hollow handle section and having a heel stand beneath said handle section and at the rear of the body of the iron, the rear side of said stand curving upwardly and rearwardly from a point adjacent the body of the iron, said handle section being counterweighted and pivotally connected at one end to the top portion of the heel stand and a spring acting upon said handle section and effective when the operator's hand is removed therefrom to rock the handle section upwardly and rearwardly into a position wherein the counterweight thereof will automatically tilt the iron bodily back 65 onto said heel stand.

3. In combination, an iron comprising a body having a hollow handle section and having a heel stand beneath said handle section and at the rear of the body of the iron, the rear side of said stand curving upwardly and rearwardly from a point adjacent the body of the iron, said handle section being pivotally connected at one end to the top portion of the heel stand, a moving counterweight within said handle section, and a spring acting upon said handle section and effective when the operator's hand is removed therefrom to rock the handle section upwardly and rearwardly into a position wherein the counterweight thereof will automatically tilt the iron bodily back 70 onto said heel stand.

In testimony whereof I affix my signature.

ARTHUR L. BAILEY.
